UNITED STATES PATENT OFFICE

HARRY W. BOLENS, OF PORT WASHINGTON, WISCONSIN

HYDRAULIC JACK

Application filed November 22, 1928. Serial No. 321,162.

This invention relates to an improvement in hydraulic jacks especially adapted for use with motor vehicles although also well adapted for various other uses and applications.

5 The present application is a continuation in part of the co-pending application of Harry W. Bolens for hydraulic jacks filed July 20, 1927, Serial No. 207,129, now Patent No. 1,709,000, granted April 16, 1929.

10 Various types of hydraulic jacks are coming into use at the present time, but all of them comprise essentially a base carrying a jack cylinder or lifting cylinder in which the ram or lifting piston of the jack is fitted. A man-

15 ually operable pump is also provided and is utilized for transferring a liquid, such as oil, from the reservoir to the lifting cylinder and beneath the lifting piston thereof. A valve controlled bypass is also provided for permitting

20 return flow of the liquid from the cylinder to the reservoir when the jack is being lowered. While these essential fundamental elements of the hydraulic jack have been organized in many different ways, the present

25 invention is applicable to practically any organization thereof in that it has to deal with the range of action of the lifting piston and the return of the lifting piston to lowered or inoperative position. It will be readily ap-

30 preciated that the size of a hydraulic jack is necessarily limited, when it is intended for use with the present types of motor vehicles, by the road clearance between the part of the vehicle which the jack engaged and the

35 ground. This road clearance varies with different vehicles and to render a hydraulic jack capable of advantageous use with different types of vehicles, it has been proposed to provide a lifting piston of the jack with an

40 extension, usually in the form of a screw, which is normally housed in the hollow lifting piston, but which may be extended therefrom as may be necessary to adapt it for use with the particular vehicle to which the jack is to be applied. The organization of such a screw

45 with the piston has given rise to rather a serious manufacturing problem involving difficult and expensive machining operations and this is especially undesirable in a device 50 of this kind as it is essential to keep the cost

of producing a jack of this type as low as possible if it is to be available to the ordinary automobile owner. It is also essential that this type of jack provide some means for returning the lifting piston of the jack to its lower or inoperative position when it is desired to move the jack from beneath the vehicle. Springs have been proposed for this purpose, but it has been found a difficult matter to organize the springs with the piston in a way that will not decrease the range of action of the piston or impair other desirable qualities or features of the jack construction.

55 One of the principal objects of the present invention resides in the provision in a hydraulic jack of a simple, reliable and effecting lifting piston extension arrangement which is susceptible of convenient and economical manufacture and which avoids the difficulties and expense of prior construction as the elements of the extension arrangement are so 60 organized and constructed as to avoid the necessity of expensive or difficult machinery operations.

65 Further, the present invention proposes in conjunction with the lifting piston extension a novel form of spring return which, while being embodied in a simple and durable construction easily applicable to the jack, does not decrease the range of action of the lifting 70 piston or in any way impair the other desirable qualities and features of the jack.

75 Other objects and advantages reside in certain novel features of the construction, arrangement and combination of parts which will be hereinafter more fully described and particularly pointed out in the appended claims, reference being had to the accompanying drawing forming a part of this specification, and in which:

80 Figure 1 is a view partly in side elevation and partly in central vertical longitudinal section showing the invention applied to one type of hydraulic jack; and

85 Figure 2 is a view partly in front elevation looking towards the left of Figure 1 and partly in transverse central vertical section.

90 In the drawing, the invention is shown applied to one type of hydraulic jack but it is to be understood that it may be utilized to 100

equal advantage with various other types of jacks, one type being shown merely for the sake of illustrating one example or embodiment of the invention. The type of jack illustrated is more fully shown and described in the pending application of Harry W. Bolens, for hydraulic jacks, filed July 20, 1927, Serial No. 207,129, now Patent No. 1,709,000, granted April 16, 1929, to which reference is made for a full disclosure of the general features of the jack construction.

As shown, the jack includes a base 1 having an integral upwardly extending lifting cylinder 2 in which a piston 3 is fitted. The piston has a hollow piston rod 4 secured thereto and sliding through a stuffing box 5 provided at the upper end of the cylinder 2. The piston rod is made up of ordinary tubing and requires no special machinery. In this type of jack, the space $2a$ above the piston constitutes the reservoir for the liquid. A manually operable pump 6 is swiveled to the base 1, the pump communicating through valve controlled passages with the interior 25 of the lifting cylinder both above and below the piston cylinder therein, so that upon manipulation of the pump 6 the liquid is transferred from the reservoir space $2a$ above the piston to beneath the piston whereby to force the piston up or elevate the jack. A suitably manipulated valve controlled bypass is provided between the space in the cylinder 2 beneath the piston 3 and the reservoir space $2a$ to permit of the return of the liquid 30 from beneath the piston to the reservoir space $2a$ independently of the pump when the jack is to be lowered.

The hollow piston rod 4 has an extension 10 in the form of a rod which slidably fits 40 within the hollow piston 4. The lower end of the rod 10 is formed with a guiding portion 11 which has free guiding contact with the interior of the piston 4. Above the guiding portion 11 the rod is screw threaded as at 45 $10a$ but these screw threads slide freely through the hollow piston rod 4.

Above the cylinder 2, a combined spring connecting member and nut 12 is provided and has its body portion abutting or resting directly on the upper end of the hollow piston rod 4. This combined spring connecting member and nut 12 has a central internally threaded opening 13 and the internal threads of this opening 13 intermesh or interfit with the external threads $10a$ of the extension rod 10. This arrangement provides an adjustable connection between the extension rod 10 and the combined spring connecting member and nut 12 which permits the extension rod to be turned to move it out of the main piston rod to the desired extent. In any adjustment, however, any load placed on the extension rod is transmitted directly through its positive structure to the main piston rod. To facilitate turning of the ex-

tension rod 10 and the consequent adjustment thereof, and to better adapt the upper end thereof to engage the element or article to be lifted, a lifting head 15 is attached to the upper end of the extension rod 10. Any desired attaching means may be provided for fixedly securing the lifting head 15 to the extension rod 10 and for the sake of simplicity in illustration, the extension rod 10 is shown as having a reduced and threaded end 10' 70 engaged with an internally threaded central opening 15' in the lifting head 15.

For the purpose of automatically lowering the piston or lifting element of the jack when the by-pass is opened, a pair of retractile coil springs 20 are provided and as shown are disposed outside of the lifting cylinder. The springs 20 parallel the lifting cylinder 2 at its opposite sides and have hook-like terminals 21 at their lower end engaged with apertured lugs 22 integral with the base 1. At their upper end the springs 20 have hook-like terminals 23 engaged with the apertured lugs provided by the downwardly and outwardly extending ends of the combined spring attaching member and nut 12. The springs 20 are under tension when the lifting element of the jack is completely lowered and tend to maintain in this position. When the lifting element of the jack is raised, the springs 20 are further stressed and tensioned and the force which these springs apply to the combined spring attaching member and nut 12 is directly transmitted at all times to the main piston rod 4 as this combined spring attaching member and nut 12 always abuts against or positively engages the upper end of this main piston rod 4. It will be obvious from the foregoing that the springs 20 do not in any way lessen the range of action 105 of the lifting element of the jack and as they are external of the cylinder, they do not complicate its construction or make it difficult to obtain a leak proof jack. While having these advantages they supply a very effective agency for lowering the lifting element of the jack at the proper time. Further, one of the elements through which the springs act, that is, the element 12 also constitutes a nut with which the extension rod of the lifting element coacts. Such a nut may be very inexpensively and conveniently produced and obviates the necessity of constructing a special type of piston rod involving difficulties in manufacture and expense. And the springs 20 provide the means which holds the nut 12 in position and against turning when the extension rod 10 is rotated to adjust its relation to the main piston rod 4.

The invention claimed is:

1. A hydraulic jack including a base, a lifting cylinder carried thereby, a lifting piston fitted in said cylinder, a hollow piston rod connected to the piston and projecting exteriorly to the cylinder, a combined spring

connecting member and nut abutting the upper end of the piston rod, retractile coil springs between the combined spring connecting member and nut and the base operating to bias the piston to its lowermost position in the cylinder and to releasably hold the combined connecting member and nut against rotation and an extension member slidably fitted in the hollow piston rod and 10 threaded through the combined connecting member and nut.

2. A hydraulic jack including a cylinder, a piston therein, a piston rod connected to the piston, an extension member freely inter- 15 fitted with the piston rod and having a screw thread, a separate nut disposed externally of the cylinder and engaged with said screw thread and with said piston rod and spring means coacting with the nut to hold it engaged with said piston rod and against rotary movement and to bias the piston and parts connected thereto to lowermost position.

In witness whereof, I have hereto affixed
my signature.

HARRY W. BOLENS.
